LOUIS JENSEN LARSEN, OF ASTORIA, NEW YORK.

SHACKLE.

Application filed September 18, 1926. Serial No. 136,368.

The present invention relates to shackles particularly of the kind used in connection with the rigging of ships and yachts, although they have many other uses. Such 5 shackles are generally characterized by a yoke having in its ends openings adapted to receive a pin which is removable and is secured in the yoke in various ways.

The general object of the invention is 10 to provide a new and improved shackle characterized by the fact that while the shackle pin is longitudinally movable in the yoke, it is not entirely removable therefrom but is always retained in cooperative relation thereto, so that there is no danger of its 15 being lost, new and improved means being provided for locking the pin in its operative position. While this shackle is particularly adapted and intended for securing a halyard 20 to an eye in a sail, it is of course well adapted to other uses, particularly where it is necessary to frequently disconnect the shackle from a sail or piece of rigging with which it normally cooperates.

25 The invention will be readily understood from the following description taken in connection with the accompanying drawing wherein Figure 1 is a front elevation partly in section of the shackle; Figure 2 is a side elevation of the shackle with a portion removed to show certain features of construction; Figure 3 is a fragmentary transverse view in section on the line 3—3 section 1; and Figure 4 is a perspective view of the 35 shackle pin forming one of the elements of the shackle. The same reference characters represent like parts in the several views.

Referring to the drawing, the shackle is shown as provided with a swivel or ring 1 40 rotatably attached to the yoke 2 of the shackle by means of a pin 3 which passes freely through a hole in the yoke and is provided with an enlarged head 4. It will be understood, however, that the ring 1 45 forms no part of the present invention. The arm 5 of the yoke is provided in its lower end with an opening adapted to receive a shackle pin 7 which is provided at one end with a head 9, the other end of said pin 50 being adapted to enter an opening in the other arm of the yoke 2. As shown in Figures 1 and 2, this last mentioned arm of the yoke 2 comprises a portion 10 which is integral with the yoke, and a cover portion 11 which is secured to the portion 10 by screws 55 12 or in any other suitable manner. As best

shown in Figure 1, the cover 11 is provided with an enlarged portion 13 which serves to enclose the end of the shackle pin 7 which projects into the arm 10.

The form of the shackle pin 7 will be understood from the drawing, particularly Figure 4. Extending longitudinally of the pin 7 throughout a considerable portion of its length is a groove 14 having a partially circumferential extension 15, this groove being adapted to cooperate with a pin 16, fixed in the yoke arm 5 and extending into the opening therein in which the pin 7 is movable. This pin and groove connection between the 70 shackle pin 7 and the arm 5 of the shackle yoke prevents the pin 7 from being completely withdrawn from the yoke, and also effectively holds the pin in its fully inserted position in the yoke when the pin 7 is rotated 75 so that the holding pin 16 is in engagement with the circumferential groove 15.

The means for yieldably holding the pin 7 against accidental rotation and displacement from its locked position, will now be described. As shown in Figures 1 and 2, the arm 10 of the yoke is provided with a cavity 19 which communicates with the opening in the arm 10 which receives the pin 7; and mounted for movement in the cavity 19 is a 80 spring 20 having a bent portion 22 which projects into the opening in the arm 10. This bent portion 22 of the spring 20 is adapted to enter a recess 24 in the shackle pin 7 near the end thereof, and thus yieldably hold the 85 pin 7 against rotation. It will be noted from the drawing that when the recess 24 is in engagement with the portion 22 of the spring 20, the holding pin 16 is in engagement with the circumferential groove 15 near the end 90 thereof. In order to force back the spring 20 when the end of the shackle pin 7 is inserted in the arm 10, the end of the pin is provided with a beveled portion 25 which, 95 acting as a cam, engages the portion 22 of the spring 20. It will be apparent that the beveled surface 25 of the pin 7, bears such a relation to the groove 14 and the recess 24 that during longitudinal movement of the pin, the spring 20 will be forced back until 100 its bent portion 22 cooperates with the cylindrical surface of the pin; and that as the pin is rotated with the locking pin 16 in engagement with the circumferential groove 15, the curved portion of the spring 20 will 105 move into the recess 24.

From the foregoing description, it will be

apparent that the shackle pin 7 may readily be moved from its inserted and locked position, shown in full lines in Figure 1, to its withdrawn position shown in dash lines in 5 that figure, by grasping the head 9 of the pin with the fingers and rotating it about a quarter turn and then moving it longitudinally. The shackle pin 7 is thus always retained in cooperative relation to the shackle 10 yoke 2, but is capable of being partially withdrawn, and is firmly retained in its inserted position against accidental displacement.

Various modifications in the form, proportion, relative size of the parts and minor details of construction may be made without departing from the spirit and scope of my invention as defined in the following claims.

I claim:

20. 1. A shackle comprising a yoke having arms provided with aligned openings, a shackle pin movable in said openings, said shackle pin having therein a groove a portion of which is longitudinal and a portion 25 of which is partially circumferential in said pin, a locking pin in one arm projecting into said groove whereby said shackle pin is retained against complete withdrawal from the yoke and is retained in its inserted position, said shackle pin also having a recess therein and a beveled end, and a spring carried by the other arm of the yoke adapted to be depressed by the beveled end of said

shackle pin, and engaging said recess only when the shackle pin is completely inserted 35 and rotated as far as is permitted by engagement of the locking pin with the end of the circumferential portion of the groove.

2. A shackle comprising a yoke having arms provided with aligned openings, one 40 of said arms being provided with a cavity which communicates with the opening therein and a cover portion covering said cavity and the outer end of said opening, a shackle pin movable in the openings in the yoke arms, 45 said shackle pin having therein a groove a portion of which is longitudinal and a portion of which is partially circumferential in said pin, a locking pin in one arm projecting into said groove whereby said shackle pin is 50 retained against complete withdrawal from the yoke and is retained in its inserted position, said shackle pin also having a recess therein and a beveled end, and a spring located in the recess in the other arm of said 55 yoke and having a portion projecting into the opening therein and adapted to be depressed by the beveled end of said shackle pin, and engaging the recess in said shackle pin only when the latter is completely inserted and rotated as far as is permitted by engagement of the locking pin with the end of the circumferential portion of the groove.

In testimony whereof, I have affixed my signature to this specification.

LOUIS JENSEN LARSEN.
